(57) **CLAIM**

The ornamental design for a water level sensing assembly, as shown and described.

DESCRIPTION

FIG. 1 is a front right isometric view of a water level sensing assembly showing my new design;

FIG. 2 is a front plan view thereof;

FIG. 3 is a top plan view thereof;

FIG. 4 is a bottom plan view thereof;

FIG. 5 is a right side plan view thereof;

FIG. 6 is a left side plan view thereof; and,

FIG. 7 is a back plan view.

The cord member being shown broken away for ease of illustration.
